United States Patent Office

Des. 231,758

Patented June 11, 1974

231,758

COUCH

Alberto Rosselli, Milan, Italy, assignor to Industria
Arredamenti Fratelli Saporiti, Besnate, Varese, Italy

Filed May 28, 1971, Ser. No. 148,305

Term of patent 7 years

Int. Cl. D6—01

U.S. Cl. D6—63

FIG. 1

FIG. 1 is a front view of a couch embodying my new design;

FIG. 2 is a side view of the couch; and

FIG. 3 is a rear view thereof.

The opposite side of the couch, not shown in the drawing, is the mirror image of the one seen in FIG. 2.

I claim:

The ornamental design for a couch, as shown and described.
